(57) **CLAIM**

The ornamental design for display screen for automobile cluster, as shown and described.

DESCRIPTION

1. Display screen for automobile cluster

1.1 : Perspective

1.2 : Front

1.3 : Back

1.4 : Left

1.5 : Right

1.6 : Top

1.7 : Bottom

1.8 : Reference view

The broken lines depict portions of display screen for automobile cluster that form no part of the claimed design; reproduction 1.1 is a front perspective view of the display screen for automobile cluster; reproduction 1.2 is a front view thereof; reproduction 1.3 is a back view thereof; reproduction 1.4 is a left view thereof; reproduction 1.5 is a right view thereof; reproduction 1.6 is a top view thereof; reproduction 1.7 is a bottom view thereof; reproduction 1.8 is a reference view showing the use state in which the claimed design has been installed on an automobile and forms no part of the claimed design; this design is for a display screen for automobile cluster and CID(center information display) together in one curved glass; there is a space between the glass and the body to give a feeling of floating.

1 Claim, 8 Drawing Sheets
